(57) **CLAIM**

The ornamental design for a dashboard, as shown and described.

DESCRIPTION

FIG. 1 is a front perspective view of a dashboard showing our new design.

FIG. 2 is a front view of the dashboard shown in FIG. 1.

FIG. 3 is a top view of the dashboard shown in FIG. 1.

FIG. 4 is a back side view of the dashboard shown in FIG. 1.

FIG. 5 is a bottom view of the dashboard shown in FIG. 1.

FIG. 6 is a left side view of the dashboard shown in FIG. 1; and,

FIG. 7 is a right side view of the dashboard shown in FIG. 1.

In the drawings, the broken lines depict portions of the dashboard that form no part of the claimed design. Applicant reserves the right to convert solid line portions to broken lines to disclaim clear distinguishable segments of the article of manufacture shown. Further, Applicant reserves the right to convert broken lines into solid lines during prosecution.

1 Claim, 7 Drawing Sheets
